DRESSER OR THE LIKE

Joseph E. Adkinson, 3807 Leland St.,
Chevy Chase, Md. 20015

Filed Apr. 20, 1970, Ser. No. 22,527

Term of patent 7 years

Int. Cl. D6—04

U.S. Cl. D33—6

The figure is a view in a perspective of the dresser.

The side of the article not shown is a mirror image of the side shown while the back is plain and unornamented.

I claim:

The ornamental design for a dresser or the like, substantially as shown and described.
